ATTORNEY

UNITED STATES PATENT OFFICE.

CHRISTOPHER H. CARLI, OF STILLWATER, MINNESOTA.

HORSE-BLANKET.

SPECIFICATION forming part of Letters Patent No. 660,414, dated October 23, 1900.

Application filed January 31, 1900. Serial No. 3,443. (No model.)

To all whom it may concern:

Be it known that I, CHRISTOPHER H. CARLI, a citizen of the United States, and a resident of Stillwater, in the county of Washington and State of Minnesota, have invented a new and Improved Horse-Blanket, of which the following is a full, clear, and exact description.

This invention relates to improvements in blankets for horses or other animals; and the object is to provide a blanket with a simple means for fastening it in place, so that it will be prevented from being blown off or slipping down around the animal's feet.

I will describe a blanket embodying my invention and then point out the novel features in the appended claims.

Reference is to be had to the accompanying drawings, forming a part of this specification, in which similar characters of reference indicate corresponding parts in both figures.

Figure 1 shows a blanket and its attachments embodying my invention as placed upon a horse, and Fig. 2 is a plan view of the blanket.

Referring to the drawings, 1 designates the body portion of the blanket, having flaps 2 at its forward end designed to overlap when placed upon an animal, as indicated in Fig. 1, thus providing a double thickness of material, serving as a chest-protector for the animal. The surcingle 4 is adapted to pass through openings 5 6 in the body portion of the blanket, and extended from the surcingle at one side is a fastening-strap 7, which passes along the outer side of the body portion of the blanket, thence across the flap 2 through an opening 8 in the flap, and thence through a loop 9 on the flap 3, and at its end this strap 7 is provided with a snap-hook 10 for engaging a ring 11, attached to the body portion of the blanket. From the opposite side of the surcingle a fastening-strap 12 extends along the body portion of the blanket, thence to the

outer side of the flap 2, and has a snap-hook connection 13 with a ring 14, attached to the 45 blanket.

While I have shown snap-hooks and rings as fastening devices, it is obvious that other suitable fastening devices may be employed without departing from the spirit of my invention.

The surcingle and fastening-straps are removable from the blanket, which will be found convenient when it is necessary to wash or otherwise clean the blanket.

Having thus described my invention, I claim as new and desire to secure by Letters Patent—

1. An animal-blanket, having flaps at its forward end adapted to overlap over the chest 60 of an animal, a surcingle, a fastening-strap extended from said surcingle through an opening in one of the flaps, a loop on the other flap through which said strap is also designed to pass, a fastening device for said strap, and 65 another fastening-strap extended from the opposite side of the surcingle and adapted to project across the other of the overlapped flaps to a connection with the blanket, substantially as specified.

2. An animal-blanket, comprising a body portion having flaps at its forward end, adapted to overlap over the animal's chest, a surcingle having removable connection with the blanket, fastening-straps connected at one 75 end to said surcingle, and adapted to pass over the flaps, and fastening devices for the ends of said straps, substantially as specified.

In testimony whereof I have signed my name to this specification in the presence of 80 two subscribing witnesses.

CHRISTOPHER H. CARLI.
